CLAIM

The ornamental design for a battery as shown and described.

DESCRIPTION

FIG. 1 is a first perspective view of a battery; FIG. 2 is a second perspective view thereof; FIG. 3 is a front view thereof; FIG. 4 is a rear view thereof; FIG. 5 is a first side view thereof; FIG. 6 is a second side view thereof; FIG. 7 is a top view thereof; and, FIG. 8 is a bottom view thereof.

The broken lines in the drawings are for the purpose of illustrating portions of the battery that form no part of the design claimed.
